Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed May 23, 1924. Serial No. 715,280.

This invention relates to typewriting machines, particularly to the ribbon mechanism thereof, and more especially to machines for writing checks or similar instruments, and for making a copy on a record-sheet of a part of the matter typed on each check of a series, the same being an improvement on my co-pending application, Serial No. 680,154, filed December 12, 1923.

One of the usual lines typed upon a check consists of the name of the payee together with the numerals indicating the amount for which the check is drawn, while the other line or lines include the amount for which the check is drawn, spelled out in full, and other data. It is desirable on the record to copy only the name of the payee and the amount of the check in numerals.

The usual carbon copies are not sufficiently permanent to suit all purposes, as the impressions are easily smeared and worn off, besides not being clear and lasting. It is therefore one of the features of the invention to provide, in addition to the usual ribbon mechanism for typewriting on the faces of the checks, an auxiliary or duplicating ribbon behind the checks, but in front of the record-sheet, and mechanism is also provided to move the auxiliary ribbon to and from its effective position.

In accordance with another feature of the invention, provision is made of a manually-operable handle arranged to be effective when moved in one direction to raise the auxiliary ribbon-carrying frame, thus moving the auxiliary ribbon to ineffective position, the handle being effective at a single stroke, when actuated in the reverse direction, to perform the dual function of restoring the auxiliary ribbon to an effective position and feeding it longitudinally across the printing point.

It is a further feature to provide a connection between the feed-roll release lever and auxiliary ribbon-carrying frame arranged to positively and directly lower the ribbon into effective position upon moving the lever upward to clamp the feed-rolls against the platen, the lever being inoperative with respect to the frame and ribbon when moved downwardly to release the rolls from the platen.

Another aim is to provide an auxiliary

ribbon with a shield held stressed at its ends by resilient or elastic supports, the shield being of a fragile nature, as, for instance, a strip of paper stretched across the front of the auxiliary ribbon to prevent the type-impressions from appearing on the back of the checks. Due to the location of the axis about which the ribbon-carrying frame is oscillated, the auxiliary ribbon when moved to its ineffective position is carried away from the platen by its end supports, but because of contact with the paper-fingers its central portion is held relatively close to the platen, stretching the ribbon and stressing the shield sufficiently to tear the same except for the resiliency of its supports or interponents, which allow the shield to bulge or protrude from said supports toward the platen when the ribbon and shield are moved upwardly to an ineffective position.

Other features and advantages will hereinafter appear.

In the accompanying drawings,

Figure 1 is a partial front elevational view of the upper portion of a typewriting machine, showing the invention as applied, parts being broken away to disclose the construction.

Figure 2 is a side elevation as seen from the right-hand end of the machine, showing the auxiliary ribbon in an ineffective position and the feed-rolls as released from the platen.

Figure 3 is a similar view, partially in section, taken in a plane further to the left than Figure 2, showing the auxiliary ribbon and its associated parts in normal operative positions, with the ribbon raising and feeding handle shown in dot-and-dash lines when moved to feed the ribbon.

Figure 4 is a partial transverse sectional view taken through the platen in a plane near the center thereof, the view omitting many of the details, being diagrammatic in character.

Figure 5 is a fragmentary perspective view, showing the preferred relative arrangement of the auxiliary ribbon and its shield, together with one of the yieldable end supports therefor.

Figure 6 is a partial plan and partial sectional view of the left-hand end shield support and auxiliary ribbon.

Figure 7 is a fragmentary perspective view, showing a modified form of yieldable support for the shield.

Figure 8 is a miniature diagrammatic view, illustrating the relative position of the platen, auxiliary ribbon and shield with its supports in effective position.

Figure 9 is a similar view of the same parts, but shown in an ineffective position.

Referring more in detail to the drawings, the numeral 10 designates the usual typewriter ribbon actuated and controlled as common in the well-known Underwood machine, as are also the type-bars 11 shown in dot-and-dash lines in Figures 3 and 4 of the drawings. The platen 12 is mounted on a shaft 13, provided with the usual line-spacing ratchet-wheel 14, and journaled in the platen-frame sides 15, connected at the rear by a plate 16, which constitutes a paper-guide or shelf, cut away to provide openings for the paper feed-rollers 17.

These rollers are mounted upon rods resting in bell-crank arms 18 pivoted upon a rod 19 journaled in the platen-frame sides 15, the other downwardly-extending arms 20 being arranged in close relation, and having between them a cam 21, actuated by a link 22 pivotally engaged with a connecting bar 23 pivoted to the inner offset portion 24 of a release lever 25. The release lever 25 is connected with the element 24 by a stud 26 rotatively mounted in the platen-frame sides, and extends forwardly into a position for convenient operation.

Adjacent the top of the platen 12 is a paper-finger-carrying rod 27 having rigid connections 28 at its ends, forwardly looped to clear certain parts of the machine, the outer ends of the looped elements being journaled in brackets 29 attached to the platen-frame sides 15, and provided with spring-pressed keys 30 to normally maintain the rod 27 in such a position that paper-fingers 31 carried thereon are held pressed against the surface of the platen, but permit forced oscillation of the rod and consequent raising of the fingers for the purpose of inserting or adjusting the paper sheets to be typed.

These paper-fingers are provided with rolls 31^a pressing upon the inner or record-receiving sheet, designated by the character B (see Figure 4), disposed directly against the platen 12, the outer sheet A passing between the paper-fingers as shown and being guided laterally by them.

A rock-shaft 32, journaled in the platen-frame sides 15, has rigidly fixed upon its ends an auxiliary ribbon frame comprising end plates 33 carrying studs 34 at their upper portions, upon which are revolvably mounted auxiliary ribbon-spools 35. These spools are provided with ratchet-wheels 36 actuated by feed pawls 37, one of which is

pivoted on a lever handle 38 and the other, at the left, on a disk 39. These pawls are raised and lowered alternately, relative to the teeth of their corresponding ratchet-wheels by means not shown, but which form the subject-matter of the co-pending application of Alfred G. F. Kurowski, Serial No. 690,705, filed February 5, 1924.

The lever handle 38 and disk 39 are rigidly engaged upon hub bushings 40 fixed on the ends of a sleeve 41, which is rotatable independently on the rock-shaft 32 by the handle 38, the handle having, near its axis, a projection carrying a fixed pin 42 movable in a slot 43 formed in the right-hand plate 33 of the ribbon frame, for the purpose of permitting a ribbon-feed movement of the lever, and a tension spring 44, fixed to the pin 42, acts to restore the handle after it has been depressed. A pin 46 is fixed on the plate 33 to oscillate the frame upon the rock-shaft when the handle 38 is moved to its extreme rearward position, as shown in Figure 2.

In moving the handle 38 toward the front, into the full-line position shown in Figure 3, the ribbon-spool frame will be rocked forward, which movement causes one of the ratchet-wheels 36 to engage its corresponding pawl 37, selectively raised into operative position by means not shown, and a further forward movement of the handle, to the dot-and-dash line position shown in Figure 3, causes rotation of the ribbon-spools.

An outstanding lug 47 set in the face of the handle 38 is engaged by a pin 48 fixed in a dog 49 pivoted on the extreme outer end of the release lever element 24, the dog 49 having an outwardly-bent ear 50 normally held against the upper edge of the release lever 24 by a spring 51. From the foregoing, it will be understood that when the handle 38 has been moved to its extreme rearward position and the feed-roll release lever 25 is thereafter depressed, the pin 48 will engage the underface of the lug 47, swinging the dog upon its pivot, and eventually tripping over said lug and releasing the pin, which thus assumes a position above the lug 47. Now upon raising the finger-piece of the lever 25, the pin 48 will contact with the upper face of the lug 47 and, due to the holding of the ear 50, will press downwardly upon the lug 47, thereby returning the ribbon frame to effective position and oscillating the handle 38 upon its axis, to cause rotation of the ribbon-spools 35 and a consequent feeding of the auxiliary ribbon 62. As the pin 48 reaches the limit of its downward stroke it slips off the edge of the lug 47 and assumes a position below the lug, the handle 38 being urged to normal position under action of the tension spring 44. (See dot-and-dash position of lug 47 in Figure 3.)

On the right hand of the rock-shaft 32 is

an arm 53 carrying a roller 54 engageable with a rearwardly-projecting portion of the adjacent plate 33, this arm limiting the upward movement of the auxiliary ribbon spool 5 frame. Fixed to the bushings 40 are cam members 55 extending rearwardly, and each is provided with a pair of spaced recesses 56 and 57, respectively, suited to engage a roller 58 rotatably mounted on the end of an 10 arm 59, pivoted at 60 to projecting brackets 61 extending from the platen-frame sides 15, these cam members determining the effective and ineffective positions of the auxiliary ribbon 62 in an obvious manner.

15 This ribbon 62 is mounted on the spools 35 to pass over guide-rollers 63, and thence through smoothly finished angular guide slots 64 in the lower front part of brackets 65 secured to the ribbon frame plates 33, 20 these guide slots turning the ribbon 62 at right angles to pass lengthwise in front of the platen. The rollers 63 are revolvably mounted in the brackets 65, formed on the plates 33, the front elements of which contain the slots 64.

A ribbon-shield 70 is disposed in spaced parallel relation with the auxiliary ribbon 62, the shield having rearwardly-bent end portions disposed interjacent gibs 67 and one 30 of the ends 71 of flat springs 72, which are openly bowed to provide a suitable degree of resiliency. Loops 66 are carried upon the ends 71 and set-screws 68 are effective to clamp the ends of the ribbon-shield 70 between the gibs 67 and the ends 71. The opposite ends 73 of the springs being secured by screws 74 to the inner walls 65^a of the brackets 65 at a point opposite the set-screws 68. Thus it will be seen that upon stressing 40 the shield 70, the springs 72 will yield, avoiding fracture of the shield under ordinary working conditions; the relative positions of the platen, auxiliary ribbon and its supports are diagrammatically shown in Figures 8 and 9, and also in the transverse sectional view Figure 4, which clearly illustrates the position of the outside paper-sheet A and copy-receiving sheet B, when the auxiliary ribbon is in its ineffective or raised position.

45 In the modification shown in Figure 7, the auxiliary ribbon 62 is shown in relation to the rollers 63 and brackets 65 in an identical manner with that described in the foregoing, but in place of the loops 66 there is attached to the lower end of each of the brackets 65 a plate 75 provided with a slot 76 near its outer edge, this slot being engageable with a hook 77 secured to an elastic element 78, such, for instance, as a rubber strap or flat tension 55 spring, and having its opposite end engaged directly and positively with the shield 70.

In both structures it will be noted that the auxiliary ribbon and shield are closely constrained against the platen at all times, 60 whether in effective or ineffective position,

thus avoiding fouling or entanglement by the outer sheet in entering it to be typed.

As the axis of oscillation of the auxiliary carrying frame is at a point above and rearward of the axis of the platen, it follows that 70 the supports at the ends of the ribbon and shield swing away from the platen as they are raised, causing the ribbon to stretch in order to accommodate itself to the condition, and entails the necessity of providing yielding, elastic mounts for the fragile and non-stretchable shield, as herein described, and which adequately fulfill their functions.

Variations may be resorted to within the scope of the invention, and portions of the 80 improvements may be used without others.

Having thus described my invention, I claim:

1. In a typewriting machine, in combination, a revolvable platen, a main ribbon for typing upon an outside work-piece, a feedable auxiliary ribbon, extending along the platen, for typing upon a work-piece disposed between said outside work-piece and the platen, a support for the auxiliary ribbon, said support being movable to shift said auxiliary ribbon into or out of printing position, a shield shifting with said auxiliary ribbon and interposed between the same and the outside work-piece, means for feeding said auxiliary ribbon along said platen, feed-rolls, a feed-roll-release lever, and devices associated with the auxiliary ribbon-feeding means and said lever and operable by the latter to cause said means to feed said auxiliary ribbon along said platen.

2. In a typewriting machine, in combination, a revolvable platen, a main ribbon for typing upon an outside work-piece, a feedable auxiliary ribbon, extending along the platen, for typing upon a work-piece disposed between said outside work-piece and the platen, supports for said auxiliary ribbon, said supports being shiftable eccentrically to the platen and away therefrom, a shield shifting with said auxiliary ribbon and interposed between the same and the outer work-piece, means for confining said auxiliary ribbon and the shield so as to follow the curvature of the platen at substantially printing distance therefrom as the supports shift said auxiliary ribbon and the shield to non-printing position, means for feeding said auxiliary ribbon along said platen, feed-rolls, a feed-roll-release lever, and devices associated with the auxiliary ribbon-feeding means and said lever and operable by the latter to shift said supports to move the auxiliary ribbon from non-printing to printing position and also to cause said ribbon-feeding means to feed said auxiliary ribbon along said platen.

3. In a typewriting machine, in combination, a revolvable platen, a main ribbon for typing upon an outside work-piece, an aux-

iliary ribbon for typing upon a work-piece disposed between said outside work-piece and the platen, feed-rolls normally engaging the platen, means for releasing or applying said feed-rolls, supports for said auxiliary ribbon, said supports moving eccentrically to the platen and away therefrom when shifting said auxiliary ribbon from effective to ineffective position, a shield shifting with 10 said auxiliary ribbon and interposed between the same and the outside work-piece, means for confining said auxiliary ribbon, the shield and the second-named work-piece closely to the platen during shifting operations, means associated with the feed-roll-controlling means and the auxiliary ribbon-supports whereby to shift said auxiliary ribbon to effective position upon applying the feed-rolls to the platen, and yielding means 20 associated with said shield for preventing rupture thereof as said auxiliary ribbon and the shield move to ineffective positions under the control of said confining means.

4. In a typewriting machine, an auxiliary 25 ribbon, a fragile shield spaced closely parallel in front of said ribbon, springs having pairs of arms, one each of the arms being rigidly fixed and the other free, clamp elements carried at the free ends of said 30 springs, said clamps being receivable of the ends of the shield, gibbs loosely engaged in said clamps, and screws in said clamps to press the gibbs into holding contact with the entered ends of the shield.

5. In a typewriting machine, a platen, an auxiliary ribbon, a fragile shield spaced closely parallel in front of said ribbon, a pair of supports shiftable eccentrically to the platen, elastic members intervening the 40 ends of said shield and said supports, and means for causing said ribbon and said shield to follow the curvature of the platen at substantially printing distance therefrom in all positions of said supports.

6. In a typewriting machine, the combination with a platen-carrying frame, a main ribbon and operating means therefor, of an auxiliary ribbon having a frame displaceably mounted on an axis eccentric to the axis 50 of the platen, a shield for said auxiliary ribbon, resilient connections for the shield carried by the auxiliary ribbon-frame, means for oscillating the last-named frame into or out of an effective position relative to the main ribbon, and means for causing said auxiliary ribbon and the shield to follow the curvature of the platen at substantially printing distance therefrom during such oscillation.

7. In a typewriting machine, the combination with a platen carrying frame, a main ribbon, feed rolls, and a lever for moving the feed rolls relative to the platen, of an auxiliary ribbon having a frame pivoted to 60 the platen frame, an inelastic fragile shield

for the auxiliary ribbon, resilient supports for said shield carried by the auxiliary ribbon frame, a lever-handle to oscillate the last named frame into effective or ineffective position, and means on the feed roll lever for oscillating the auxiliary ribbon frame into effective position coincidentally upon restoring the feed rolls to the platen.

8. In a typewriting machine, the combination with a platen carrying frame, a main 75 ribbon, feed rolls, and a lever for moving the feed rolls relative to the platen, of an auxiliary ribbon having a frame pivoted to the platen frame, a shield in front of said auxiliary ribbon carried on the frame thereof, 80 a handle for oscillating the last named frame into either of its two predetermined positions, a lug on said handle, a dog pivoted on the feed roll control lever, and means associated with said dog causing operative 85 engagement with said lug upon the up-stroke of said lever, said dog being inoperative at the down-stroke of the lever.

9. In a typewriting machine, the combination with a platen, a frame therefor, feed 90 rolls for the platen, an operating lever for the feed rolls, a main ribbon, and an auxiliary ribbon, of a support frame for the auxiliary ribbon pivotally mounted on the platen frame, a handle for oscillating the 95 ribbon frame into effective or ineffective positions relative to the printing point, means for maintaining said ribbon frame in either of its adjusted positions, a lug on said handle, and a dog pivoted on the feed-roll lever, 100 said dog permitting unrestricted movement of the handle in either direction and also a downward movement of the lever, but operatively engaging said lug to oscillate the ribbon frame during an upward movement 105 of the lever.

10. In a typewriting machine, the combination with a platen, a frame therefor, feed rolls for the platen, an operating lever for the feed rolls, a main ribbon, and an auxiliary ribbon, of a support frame for the auxiliary ribbon pivotally mounted on the platen frame, a handle for oscillating the ribbon frame into effective or ineffective positions relative to the printing point, means 110 for maintaining said ribbon frame in either of its adjusted positions, a lug on said handle, means for resiliently retaining the handle in a normally raised position, and a spring-pressed dog pivoted on said lever, 115 said dog having a stop engaging the lever and a part projecting to engage said lug when the lever is oscillated, said dog yielding upon contact with the lug when the lever is moved to release the rolls and rigid when making contact with the lug during roll restoring movement of the lever, said dog being out of the path of the lug when said lever is in either of its extreme positions.

11. In a typewriting machine, the combi- 120 125 130

- nation with a revolute platen, resilient paper fingers associated therewith and a main ribbon for writing upon an outside sheet, of an auxiliary ribbon for writing 5 upon an inside sheet, means for moving the auxiliary ribbon into effective and ineffective positions, a shield disposed over said auxiliary ribbon, said shield moving therewith, said auxiliary ribbon and shield being held 10 by said fingers closely to the platen irrespective of their positions, and elastic supports for the shield permitting it to yield in accordance with the stretch of the auxiliary ribbon when in ineffective position.
- 15 12. In a typewriting machine, the combination with a revolute platen, feed rolls co-operative therewith, a lever controlling the feed rolls, and a main ribbon for writing upon an outside sheet, of an auxiliary ribbon 20 disposed behind the outside sheet for writing upon an inside sheet, a handle to move the auxiliary ribbon to an ineffective position, means on said lever operative when restoring the feed rolls to actuate said handle rendering the auxiliary ribbon effective, and a spring-stressed shield disposed over the outer surface of the auxiliary ribbon.
- 25 13. In a typewriting machine, the combination with a revolute platen, resilient paper fingers associated therewith, and a main ribbon for writing upon an outside sheet, of an auxiliary ribbon for writing upon an inside sheet, means for moving the auxiliary ribbon into effective and ineffective 30 positions, a shield disposed over said auxiliary ribbon, said shield moving therewith, rolls on the paper fingers to clamp the inside sheet upon the platen, said paper fingers normally retaining the auxiliary ribbon and shield relatively close thereagainst in any position they may assume, and means for elastically supporting the shield to permit it to follow the auxiliary ribbon without fracture.
- 35 45 14. In a typewriting machine, the combination with a revolute platen, paper fingers thereover, and a main ribbon for writing upon an outside sheet, of an auxiliary ribbon for writing upon an inside sheet, a shield disposed over the outer side of the auxiliary ribbon, supports for said auxiliary ribbon and shield, said supports being movable eccentrically to the platen, said paper fingers confining the auxiliary ribbon and shield 40 closely to the platen, means for oscillating said supports to bring the ribbon into effective and ineffective positions, and intervening resilient means between the ends of the shield and its supports.
- 45 60 15. In a typewriting machine, the combination with a revolute platen, feed rolls co-operative therewith, a lever controlling the feed rolls, and a main ribbon for writing upon an outside sheet, of an auxiliary ribbon 55 disposed behind the outside sheet for writing upon an inside sheet, when interposed between the main ribbon and platen, a frame carrying said auxiliary ribbon, said frame being pivoted on a different axis from that of the platen, a handle for oscillating 70 said frame to move the auxiliary ribbon into typing or non-typing positions, a dog pivoted on the feed roll control lever, said dog being ineffective to swing the ribbon frame when the lever releases the feed rolls, but effective to swing the ribbon frame into 75 typing position when the lever applies the rolls, a shield for the auxiliary ribbon, and elastic connections between the ends of said shield and the ribbon frame.
- 80 16. In a typewriting machine, in combination, a revolute platen, regular ribbon-mechanism, an auxiliary ribbon, a shield covering one side of said auxiliary ribbon, movable supports mounted eccentrically to 85 the axis of the platen and operable to shift the auxiliary ribbon and the shield into or out of the typing zone, confining means beneath which said ribbon and the shield move during shifting operations, and yieldable means forming connections between the opposite ends of the shield and the adjacent supports, for preventing rupture of said shield as it moves with the ribbon to any 90 position under the control of said confining 95 means.
17. In a typewriting machine, in combination, a revolute platen, regular ribbon-mechanism, an auxiliary ribbon, movable supports mounted eccentrically to the axis 100 of the platen and operable to shift the auxiliary ribbon into or out of the typing zone, a shield for the ribbon, elastic strips connecting the supports with the opposite ends of the shield, and means for confining the 105 ribbon and the shield closely to the platen in all positions to which the supports are moved, said strips preventing rupture of the shield during such movement.
18. In a typewriting machine, in combination, a revolute platen, a displaceable support, a ribbon carried by the support and extending along the platen at the printing line, means for feeding the ribbon, feed-rolls, a feed-roll release lever, and devices associated with the ribbon-feeding means and said release lever and operable by the latter to shift said support to restore the ribbon from a displaced position away from the printing line to a position at the printing line, and also effective to feed the ribbon along the platen as said ribbon is restored to said printing line.
19. In a typewriting machine, in combination, a revolute platen, a displaceable support, a feedable ribbon carried by the support and normally extending along the platen at the printing line, a ribbon-supply spool and a take-up spool carried by the support, means for operating said spools, where-
- 110
115
120

130

- by to feed the ribbon along the platen, the support being displaceable to shift the ribbon with the spools to non-printing position, feed-rolls, a feed-roll release lever, and devices associated with the ribbon-feeding means and the release lever and operable by the latter to cause the spool-operating means to feed the ribbon along the platen and also to move the support in a manner to restore the ribbon to the printing line.
20. In a typewriting machine, in combination, a revoluble platen, regular ribbon-mechanism, displaceable supports, an auxiliary ribbon carried by said supports and normally extending along the platen at the printing line, the supports being effective when displaced to remove the auxiliary ribbon from the printing line, a shield interposed between the auxiliary ribbon and the main ribbon, said shield including elastic elements at the opposite ends thereof and hooks carried at the ends of said elastic elements and engaging perforations in said supports, whereby to hold the shield tensioned in front of the auxiliary ribbon, and means for confining said ribbon and the shield to the curvature of the platen as the supports shift said ribbon and the shield from the printing line.
21. In a typewriting machine, in combination, a revoluble platen, regular ribbon-mechanism, a displaceable support, an auxiliary ribbon carried by said support and normally extending along the platen at the printing line, the support being effective when displaced to remove the auxiliary ribbon from the printing line, a shield interposed between the auxiliary ribbon and the main ribbon, said shield including elastic elements at the opposite ends thereof and hooks carried at the ends of said elastic elements and engaging perforations in said support, whereby to hold the shield tensioned in front of the auxiliary ribbon, and curved fingers adjacent the platen and under which the ribbon and the shield extend for confining them to the curvature of the platen at substantially printing distance therefrom as the displaceable frame shifts to remove the auxiliary ribbon and the shield from the printing line.
